UNITED STATES PATENT OFFICE.

VERNON ROYLE AND VERNON E. ROYLE, OF PATERSON, NEW JERSEY.

BRACKET.

1,029,228.

Specification of Letters Patent. Patented June 11, 1912.

Application filed November 25, 1910. Serial No. 594,170.

To all whom it may concern:

Be it known that we, VERNON ROYLE and VERNON E. ROYLE, citizens of the United States, and residents of Paterson, in the 5 county of Passaic and State of New Jersey, have invented a new and useful Bracket, of which the following is a specification.

Our invention relates to a bracket and more particularly to a bracket for securing 10 an electric motor-starting box to the supporting pillar or frame of a machine, the object being to provide a bracket of light, simple construction adapted to hold the box upright when attached to a slanting frame 15 or pillar, and which, in its simplest form, may be used to attach the box to an upright support or to the underside of a horizontal support at pleasure.

A practical embodiment of the invention 20 is represented in the accompanying drawings, in which,

Figure 1 shows the bracket in holding position against a slanting pillar, Fig. 2 is a view of the same in front elevation 25 with pillar removed, Fig. 3 is a view in side elevation, partly in section, of a bracket suitable for attaching a box to the upright face of a frame or pillar, Fig. 4 shows the same in front elevation with 30 frame or pillar removed, Fig. 5 shows the same in use to suspend a box from the under side of a table or horizontal support, and Fig. 6 is a top plan view of the bracket in the plane of the line A—A of Fig. 5.

Referring to the form shown in Figs. 1 and 2, the slanting supporting pillar is denoted by 1 and the box to be supported by the bracket is indicated in dotted lines. The bracket is of skeleton triangular form, the 40 three apexes, denoted by 2, 3 and 4, being provided with sockets screw-threaded or plain, for receiving retaining screws in a manner shown in section in the modified form in Figs. 3 and 5. The walls of these 45 sockets form legs, those at the apexes 3 and 4 being of the same length and denoted by 5, (Fig. 1) and the one at the apex 2, denoted by 6, being longer than the legs 5, to place the bracket in an upright position

when the ends of the three legs are placed 50 against the side of the pillar. For attaching the box to the bracket, short extensions project from the bracket preferably at or near the three apexes, denoted by 7, 8 and 9, and these are provided with sockets for 55 receiving box retaining screws or bolts, as shown in Fig. 5.

In the modified form shown in Figs. 3 to 6 inclusive, the socket legs, here denoted by 10, 11, 12, are of substantially the same 60 length and the extensions for attaching the box to the bracket, denoted by 13, 14, 15, project from the walls of the sockets.

In Fig. 3, a screw 16 is shown passing through a smooth bore socket 17 in the 65 bracket and into a screw-threaded hole in the pillar, while in Fig. 5, screws 18 are shown passing through smooth bores in the pillar wall and into screw-threaded sockets in the bracket. The screws for attaching 70 the box to the bracket are denoted by 19.

The bracket constructed as above is light, strong and convenient to manipulate and serves to locate the box in a convenient position on the machine whatever be the particular structure of the machine supporting 75 frame.

What we claim is:

1. The box supporting bracket of skeleton angular form provided with perforated legs 80 at its apexes for securing it to a support and with perforated extensions directed laterally from its margin for securing it to a box.

2. The box supporting bracket of triangular form provided with perforated legs 85 of varying lengths at its apexes for securing it to a support and with perforated extensions for securing it to a box.

In testimony, that we claim the foregoing as our invention, we have signed our names 90 in presence of two witnesses, this seventh day of November A. D. 1910.

VERNON ROYLE.
VERNON E. ROYLE.
